UNITED STATES PATENT OFFICE.

HARRY BLAISDELL, OF ST. LOUIS, MISSOURI, ASSIGNOR OF ONE-THIRD TO
CHARLES A. STIX, OF SAME PLACE.

SMOKE-CONSUMER.

SPECIFICATION forming part of Letters Patent No. 398,688, dated February 26, 1889.

Application filed September 17, 1888. Serial No. 285,608. (No model.)

To all whom it may concern:

Be it known that I, HARRY BLAISDELL, of the city of St. Louis, in the State of Missouri, have invented a certain new and useful Im-

5 provement in Smoke-Consumers, of which the following is a full, clear, and exact description, reference being had to the accompanying drawings, forming part of this specification, and in which—

10 Figure I is a side elevation illustrating my improvement. Fig. II is a front view, part in section. Fig. III is a vertical transverse section taken on line III III, Fig. I. Fig. IV is an enlarged detail section taken on line IV IV, Fig. II. Fig. V is an enlarged section of the siphon, taken on line V V, Fig. I.

15 My invention relates to an improved smoke-consumer for use in connection with steam-boilers; and my invention consists in features 20 of novelty hereinafter fully described, and pointed out in the claim.

Referring to the drawings, 1 represents a steam-boiler, having the usual smoke-stack, 2, and drum 3.

25 4 represents the brick-work or "setting," and 5 the fire-box.

6 represents a steam-pipe extending from the drum 3 downwardly into the combustion-chamber between the walls of the setting and 30 the boiler, where it has preferably a number of return-bends, and from where it extends to a pipe, 7, at the front end of the boiler. One end, 7^a, of the pipe 7 extends into the base of the smoke-stack, and the other end extends 35 downward and enters the upper portion of the front end of the fire-box, being preferably bent, as shown by dotted lines, Fig. II, to fit around the bottom of the boiler close up against the front plate of the furnace. This 40 end of the pipe 7 is perforated, as shown at 10 in Fig. IV, and it is preferably protected from the heat by a crating, 11, of fire-proof material. At the junction of the pipes 6, 7, and 7^a I insert an injector, 12, having a regulating-valve, 13, (see Figs. II and V,) which

injector projects axially into the pipe 7 past or beyond the pipe 7^a, so that the steam will enter the pipe 7 only, and thus produce the desired suction or siphon in the pipe 7^a.

The operation is as follows: The steam 50 passes from the drum 3 through the pipe 6 and is superheated, owing to the pipe being located within the combustion-chamber of the furnace. From the pipe 6 it passes through the injector into the pipe 7, and in doing so 55 creates a suction within the pipe 7 that causes the unconsumed products of combustion and gases to be taken from the breech or base of the smoke-stack through the funnel 8 into the pipe 7, where they are united with the 60 superheated steam and discharged into the fire-box through the perforations 10. (See arrows, Figs. I and IV.) In this way I form a very cheap and effective smoke-consumer.

I claim as my invention—

In a smoke-consumer, the combination, with the boiler, the setting in which said boiler is mounted having a fire-box and the smoke-stack, of the perforated pipe 7, extending under the boiler in juxtaposition thereto and to 70 the forward end of the fire-box and curved to the contour of said boiler, a fire-proof crating around said pipe, having openings complementary to the perforations therein, an inverted funnel in said stack, a pipe, 7^a, connecting said funnel with pipe 7 at right angles thereto, the pipe 6, an injector-nozzle extending from said pipe 6 axially into pipe 7 beyond pipe 7^a, a cock for regulating the flow from said nozzle, and said pipe 6 extending 75 from the steam-space to the boiler and connected to the lower one of a number of return-bends located between the boiler and the setting, forming a superheating-coil, and the pipe 7 being connected to the upper one 80 of said bends, as set forth.

HARRY BLAISDELL.

In presence of—

BENJN. A. KNIGHT,
EDW. S. KNIGHT.
